UNITED STATES PATENT OFFICE

97,184

DESIGN FOR TEXTILE FABRIC

Curt Erwin Forstmann, Montclair, N. J.

Application May 13, 1935, Serial No. 56,819

Term of patent 14 years

To all whom it may concern:

Be it known that I, Curt Erwin Forstmann, a citizen of the United States, residing at Montclair, in the county of Essex and State of New Jersey, have invented a new, original, and ornamental Design for Textile Fabric, of which the following is a specification, reference being had to the accompanying drawing, forming a part thereof.

In the drawing, the sole figure of which is a plan view of a piece of the textile fabric embodying the design of the present invention, the cloth depicted is of a single color.

The design consists of vertical rows of parallelograms arranged zig-zag in the rows, alternate parallelograms *a* being of fine texture, and the intervening parallelograms *b* being of coarse pebbled texture, adjacent rows being so displaced that the parallelograms of pebbled texture of one row come laterally next to the parallelograms of fine texture of the adjacent rows.

I claim:

The ornamental design for textile fabric as shown and described.

CURT ERWIN FORSTMANN.
